UNITED STATES PATENT OFFICE.

JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

MACHINE FOR MAKING BOLTS AND THE LIKE.

1,168,855.

Specification of Letters Patent. Patented Jan. 18, 1916.

Application filed September 25, 1911. Serial No. 651,016.

To all whom it may concern:

Be it known that I, JOHN R. BLAKESLEE, a citizen of the United States, and a resident of Cleveland, county of Cuyahoga, and State of Ohio, have invented a new and useful Improvement in Machines for Making Bolts and the like, of which the following is a specification, the principle of the invention being herein explained and the best mode in 10 which I have contemplated applying that principle so as to distinguish it from other inventions.

The present improvements relating as indicated to machines for making bolts and 15 the like, have regard more particularly to the upsetting of the end of the bar or rod constituting the stock or body of the bolt, in order to form a head thereon.

The object of the invention is to provide 20 a mechanism of this sort wherein the tendency to form fins, or, in other words, for the metal to escape from between the gripping dies and heading tool, is substantially entirely eliminated, thus rendering it possible to quickly and by a single operation to 25 form a complete and satisfactory head.

To the accomplishment of these and related ends the invention, then, consists of the means hereinafter fully described and 30 particularly pointed out in the claims.

The annexed drawings and the following description set forth in detail certain mechanism embodying the invention, such disclosed means constituting, however, but one 35 of various mechanical forms in which the principle of the invention may be used.

In said annexed drawings: Figure 1 is a plan view of the portion of a forging or upsetting machine wherein the present improvements are incorporated; Fig. 2 is a central, vertical section of such machine taken on the line 2—2, Fig. 1; Figs. 3 and 4 are transverse sections of the same respectively taken on the lines 3—3 and 4—4, Fig. 40 2; while Figs. 5 and 6 are corresponding horizontal sectional views of said machine respectively showing the parts in operative 45 positions different from each other and from that shown in Fig. 2.

Only so much of the general frame 2 of the machine is illustrated in the foregoing figures as is deemed necessary in order to

show the manner in which the various operative parts of present interest are supported. These parts include two relatively 55 transversely movable gripping dies 2, 2, which have their inner faces formed with complementary recesses adapted to receive and grip the work when said dies are forced together. Movable longitudinally of the 60 line of feed of the work, or in other words, at right angles to such direction of relative movement of the dies 2, is a header slide 3, shown in retracted position in Figs. 1 and 2, in partially advanced position in Fig. 5, 65 and in fully advanced position in Fig. 6. The detailed construction of this header slide will next be set forth.

Secured to the forward end of the header slide by a suitable clamp collar 4 and set-bolt 5, is an extension 6, preferably cylindrical in form, that is of reduced diameter at its outer end and furthermore formed with an annular recess just back of such end so as to provide an under-cut head 7. This 70 extension 6 lies within a recess in the header slide that extends to the front end thereof and is bridged at an intermediate point by a cap-plate 8. This cap-plate, which is readily removable from the side portions of 75 the slide by simply loosening bolts 9, forms a sort of housing, when taken in conjunction with the lower portion 10 of such header slide, such housing affording a bearing for a sleeve 11, that in turn is mounted upon the 80 header-slide extension 6.

This sleeve 11, like housing 8, is composed of two separable parts bolted together, and is formed with an enlargement 12 at its forward end that forms a holder adapted to 90 receive a forming die 13, such die being secured therein by means of a set bolt 14 and being thus readily exchangeable with others of different size bore. The bore in such die, it will be understood, is of the form and size 95 which it is desired to give to the bolt head in a transverse plane. There is also supported in the sleeve 11 an upsetting or heading tool 15, the forward end of the latter extending into the bore of this forming die 100 13, while its rear end has a recessed or undercut head 16 similar to the head 7 at the forward end of the header extension. The tool is secured to the header extension by

means of a split collar 17 having an internal circular recess, that, when the two portions of the sleeve 11 are drawn together, fits snugly around the juxtaposed, undercut heads in question, and thus locks the parts together.

The sleeve 11, which it will thus be seen is reciprocable upon the aforesaid forward cylindrical extension 6 of the header slide, 10 is normally retained in an extreme forward position, determined by the engagement of a lug 18 on the rear end of said sleeve with the housing 8, by means of two compression springs 19, one on each side of said sleeve. 15 These springs lie between the enlarged forward end 12 of the sleeve and suitable lateral projections 20 from housing 8, and are mounted on guide-rods 21, that are secured at their forward ends in the end 12 of the 20 sleeve and slidably rest in holes in projections 29.

Projecting upwardly from the bed of the machine is a lug 22 that forms a stop, with which the enlargement 12 on the sleeve is 25 adapted to engage, upon the retraction of such sleeve along with the header slide. This stop is so positioned as to engage the enlargement in question, when the stop has been brought back just a trifle beyond its 30 normal position, its object being to prevent the sleeve from sticking either on the extension 6, or in its bearing within housing 8, and thus remaining in its rearmost position relatively to the header-slide 35 proper, as it will more fully appear from a description of the general mode of operation of the machine.

Such general operation should be readily understood from the foregoing description 40 of the construction of the parts that enter into the present improved bolt header. The stock 23, in the form of a rod or bar, is suitably fed through the feed opening and between the gripping dies 2, so as to cause 45 the proper length of material to project beyond said die, as shown for example in Fig. 2. Thereupon the header slide advances, with the parts in the relative positions illustrated in the same figure, so that the forming die 13, that is held in the forward enlarged portion of the sleeve 11, is brought 50 against the faces of said gripping dies, thus entirely surrounding the advanced portion of the stock. Further advance movement 55 of the slide compresses the springs 19 and thus causes the extension 6 that carries the upsetting tool 15, to move within the sleeve, which now remains stationary. The upsetting tool, accordingly, is brought forcibly 60 against the portion of the stock inclosed within such forming die and compresses the same to fill the space left for the bolt head. The amount of material of course is accurately gaged so as to just fill this space. 65 The slide is now retracted, the initial effect

of this being to withdraw the header tool to its inoperative position within the sleeve and the forming die carried thereby; then the sleeve itself is withdrawn, leaving the bolt head completely formed. 70

As previously indicated, in describing the construction of the header, should the springs 19 for any reason fail to thus restore the sleeve to its advanced position relatively to the header tool, the stop 22 on 75 the bed of the machine, by engaging the enlargement on said sleeve, will prevent its being carried back too far.

A perfect inclosure being provided around the portion of the stock that is to be upset, 80 before the upsetting operation begins, none of the metal can escape, and as a result the head has none of the objectionable fins or projections hereinbefore referred to.

The operation of the mechanism is obviously simple and expeditious, and avoids the necessity for any further trimming operation such as is necessary, if a satisfactory head is to be produced with machines 85 of the prevailing construction. 90

The adjustment of the machine for the formation of heads of different shapes and sizes is readily effected by simply changing the forming die and the header tool, the other parts of the machine remaining the 95 same.

Other modes of applying the principle of my invention may be employed instead of the one explained, change being made as regards the mechanism herein disclosed, 100 provided the means stated by any of the following claims or the equivalent of such stated means be employed.

I therefore particularly point out and distinctly claim as my invention:— 105

1. In mechanism of the class described, the combination with dies for gripping the stock; of a reciprocable slide; a forward extension fixed to said slide; a housing fixed to said slide; a reciprocable sleeve interiorly bearing on said extension and exteriorly bearing in said housing, said sleeve being provided with a projection adapted, in the forward position of the sleeve, to engage said housing; a heading die removably secured to the forward end of said sleeve and having a bore adapted to inclose the stock and of the cross-sectional form desired; an up-setting tool removably secured to the forward end of said extension and reciprocably fitted in the bore of said heading die; and a relatively fixed projection adapted to engage said sleeve to limit its retraction. 115 120

2. In mechanism of the class described, the combination with dies for gripping the stock; of a reciprocable slide; a heading die reciprocably mounted on said slide and adapted to abut against said gripping dies, said heading die having a bore adapted to inclose the stock and of the cross-sectional 125 130

form desired; an upsetting tool fixedly secured to said slide and reciprocably fitted in such bore; resilient means tending to advance said heading die; and means adapted 5 during retraction of the slide, to limit retraction of the heading die and permit further retraction of the slide.

Signed by me this 21st day of September, 1911.

JOHN R. BLAKESLEE.
